US00D645652S

(12) **United States Design Patent**
Torrance et al.(10) **Patent No.:** US D645,652 S
(45) **Date of Patent:** ** Sep. 27, 2011(54) **CYCLING SHOE**(75) Inventors: **Tony L. Torrance**, Boulder, CO (US);
Charles P. Roth, Portland, OR (US)(73) Assignee: **DashAmerica, Inc.**, Louisville, CO (US)(**) Term: **14 Years**(21) Appl. No.: **29/388,010**(22) Filed: **Mar. 23, 2011****Related U.S. Application Data**

(62) Division of application No. 29/338,197, filed on Jun. 5, 2009, now Pat. No. Des. 636,983.

(51) **LOC (9) Cl.** ..... 02-99(52) **U.S. Cl.** ..... D2/969(58) **Field of Classification Search** D2/896,

Primary Examiner — Dominic Simone(74) *Attorney, Agent, or Firm* — Sheridan Ross P.C.(57) **CLAIM**

The ornamental design for a cycling shoe, as shown and described.

DESCRIPTION

FIG. 1 is top plan view of a cycling shoe design of our new design;

FIG. 2 is right side view thereof;

FIG. 3 is left side view thereof;

FIG. 4 is front view thereof; and,

FIG. 5 is rear view thereof.
